CONTAINER

Carl G. Hilgenberg, Baltimore, Md., assignor to
Carr-Lowrey Glass Co., Baltimore, Md.

Application June 17, 1936, Serial No. 85,801

1 Claim. (Cl. 215—1)

This invention relates to jars and like containers such as used for holding mustard, food dressing, and other substances to be dispensed by the use of a spoon, spatula or similar article.

5 As is well known to those accustomed to the use of such articles, it frequently happens that no convenient place is provided for the dispensing device after it has been used and, as a result, the spoon or the like frequently is deposited either 10 accidentally or intentionally upon the table or other supporting structure and soils it.

An object of the present invention is to provide a container having means formed therein for use as a supporting ledge or shoulder on 15 which a spoon or other dispensing element can rest in an upwardly extended position while not in use, so that it is always readily accessible.

A further object is to provide a container of 20 this character which can be made of glass by the usual methods of manufacture.

With the foregoing and other objects in view which will appear as the description proceeds, the invention consists of certain novel details of construction and combinations of parts hereinafter 25 more fully described and pointed out in the claim, it being understood that changes may be made in the construction and arrangement of parts without departing from the spirit of the invention as claimed.

30 In the accompanying drawing the preferred forms of the invention have been shown.

In said drawing

Figure 1 is a central vertical section through a jar having a plurality of supporting ledges or 35 pockets for engagement by a spoon, spatula or the like when not in use, the position of one of these forms of dispensing devices being indicated by broken lines.

Figure 2 is a section on line 2—2, Figure 1.

40 Figure 3 is a vertical section through the upper portion of another modified form of container.

Figure 4 is a section on line 4—4, Figure 3.

Figure 5 is a plan view of the container shown in Figure 3.

45 Referring to the figures by characters of reference 1 designates a jar formed preferably of glass and of any desired size and configuration. The neck 2 is formed with a wide mouth as ordinarily so as to be capable of receiving a spoon or other 50 dispensing device used for removing the contents of the container.

Formed within the neck portion of the container are a desired number of looped or substantially U-shaped ribs 4 forming pockets the 55 side or upwardly extending side portions of

which merge one into the other as indicated at 5 to provide reinforcements and for guiding a dispenser into position in the pockets and on the ribs.

The open space or clearance left between these 5 ribs or loops 4 is sufficiently large to permit the downward insertion therebetween of the dispensing article which, in the structure illustrated in Figures 1 and 2 is in the nature of a spatula A. The lower portions of the ribs 4 constitute ledges 10 or shoulders each of which presents an area of sufficient size to be engaged by the lower end of the dispensing device so as to support it within the neck portion 2 with its upper end projecting outwardly from the container. Thus it will be 15 apparent that after the dispensing device has been used for removing part of the contents of the container, it can be placed in an inclined position with its lower end resting on one of the ledges 4 and its other end supported outside of 20 the container where it can be grasped readily.

In Figures 3, 4 and 5 the neck portion 8 of the container 9 has been shown provided with a single loop rib or ledge providing a pocket having a supporting shoulder 10 adapted to be engaged by 25 the end of the spoon B when placed in the neck portion. A single looped rib of this type is especially useful in a container neck of small proportions from which material is to be removed by means of a spoon. In other words where only 30 one looped supporting portion is provided, any spoon substantially equal to but less than the interior diameter of the neck 8 can be inserted without interference by the shoulder or rib 10.

The containers thus far described can all be 35 produced by the usual methods of glass manufacture, it merely being necessary to utilize neck pins of special construction during the initial moulding operation.

Inasmuch as the container herein described is 40 to be formed of glass, a problem sometimes arises in the course of manufacture as to how to prevent the ribs 4 or 10 from becoming distorted while the glass is still in a plastic condition. In the form shown in Figures 1 and 3 this problem 45 has been solved by looping the ribs so that each rib has a side portion extending toward the open mouth of the neck. The side portions of the loops thus constitute supports or stiffening means for the intermediate portions of the loops 50 during the shaping operation and distortion is eliminated. Furthermore after the formation of the container has been completed, the side portions of the looped ribs not only act as longitudinal reinforcements for the neck of the container 55

but they also serve as guides whereby the lower end of a dispenser will be properly directed to its supporting pocket or shoulder when inserted into the container. It will be noted, furthermore, 5 that the ribs form dispenser receiving pockets and those portions of the ribs constituting the supporting shoulders for the dispenser are not extended in a plane perpendicular to the longitudinal axis of the neck but are inclined upwardly toward the open end of the neck so as to 10 form recesses for the reception of the lower end of the dispenser, thus eliminating danger of the dispenser slipping off of its supporting shoulder and dropping into the main portion of the 15 container.

It will be noted that in all of the forms of the device herein described and shown, the support-

ing ledge or shoulder cooperates with the upper end of the wall of the neck portion to hold the supported dispensing device in an upwardly extended position.

Obviously other modifications of the invention 5 may be made within the scope of the appended claim.

What is claimed is:

A container including a neck portion, and a substantially U-shaped rib extending inwardly 10 from the inner surface of the neck portion with its ends extended toward the mouth of the bottle and constituting guides for an object being inserted into the neck of the bottle and the bottom portion of said rib constituting a support for said 15 object when inserted.

CARL G. HILGENBERG.
